UNITED STATES PATENT OFFICE.

WILLIAM HENRY POLLGREEN, OF BISBEE, ARIZONA.

BOTTLE.

1,201,096.

Specification of Letters Patent. Patented Oct. 10, 1916.

Application filed December 21, 1914. Serial No. 878,366.

To all whom it may concern:

Be it known that I, WILLIAM H. POLLGREEN, a subject of the King of Great Britain, residing at Bisbee, in the county of Cochise and State of Arizona, have invented certain new and useful Improvements in Bottles; and I do hereby declare the following to be a full, clear, and exact description of the invention, such as will enable others skilled in the art to which it appertains to make and use the same.

This invention relates to bottle structures and more particularly to a neck and stopper structure for a bottle by means of which the fraudulent refilling of the bottle is prevented.

The primary object of this invention is the provision of a stopper which fits snugly and firmly within a flared bottle neck forming practically an air tight seal therefor and which has associated therewith a pair of transversely extending spring pressed pins which move into engagement with openings formed in the sides of the bottle neck for preventing removal of the seal or stopper without breaking the neck of the bottle.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views and in which:—

Figure 1 is a central section through a bottle stopper constructed in accordance with this invention, and Fig. 2 is a cross sectional view on the line 2—2 of Fig. 1.

Referring more particularly to the drawings, 1 designates the bottle body which has an outwardly flared neck 2 formed integrally therewith. The neck 2 is formed substantially in the shape of a frusto cone and it has its apex positioned downwardly and formed integrally with the upper portion of the body 1 of the bottle. The neck 2 is provided with bulges 3 which are disposed diametrically opposite each other and extend outwardly from the contour of the neck 2. The bulges 3 are provided for reinforcing the neck structure 2 and they have recesses 4 formed therein and extending in-

wardly from the inner wall of the neck 2. The openings or recesses 4 extend transversely into the bulges 3 as is clearly shown in Fig. 1 of the drawings. The substantially frusto-conical shaped bottle neck 2 is provided with a bore 5 which is substantially frusto-conical shaped. The bottle has the point of juncture between the body portion thereof and the neck provided with an internal thickened portion to provide a seat 6, the said thickened portion having a straight bore 7 extending therethrough, and communicating with the interior of the bottle body 1. The seat 6 has a disk 8 of cork, rubber or other resilient material mounted thereon against which the bottom or inner end of the stopper 10 rests. The stopper or seal 10 has its upper end hermetically sealed and it has a tube 11 extending transversely therethrough substantially equi-distant of the top and bottom of the stopper or seal. The tube 11 has positioned therein a pair of rods 12 and 13, which rods have enlarged heads 14 and 15 formed upon their inner ends. The enlarged heads 14 and 15 fit snugly within the diameter of the tube 11 and an expanding spiral spring 16 is positioned intermediate their facing surfaces and bears against the inner surfaces of the heads tending to force the pin 13 outwardly at all times. The pins 12 and 13 project through the side walls of the stopper or seal 10 and are provided for seating into the recesses 4 which are formed in the bulges 3.

In inserting the stopper or seal 10 in the mouth of the bottle neck, the pins 12 and 13 are forced inwardly, compressing the spring 16 and the stopper is inserted in the flared neck 2 so that the pins will be in alinement with the recesses 4 when they reach an elevation parallel therewith. Immediately upon the alinement of the pins with the recesses 4, the pins will spring outwardly, by the expanding of the spiral spring 16 and automatically seat themselves in the recesses 4, preventing the removal of the proper pin from within the neck 2 of the bottle.

In reducing the invention to practice certain minor features of construction, combination and arrangement of parts may necessitate alterations to which the patentee is entitled provided such alterations are comprehended within the scope of what is claimed.

What is claimed is:—

- A bottle consisting of a body portion, a neck formed on the upper end of the body portion, the point of juncture between the body and the neck being internally thickened to provide a seat, the said thickened portion having a straight bore extending therethrough and communicating with the interior of the bottle, the said neck having
1) a bore of a downwardly decreasing diameter having the lower ends of the walls thereof terminating at the seat, the walls of the bore in the neck having diametrically opposed recesses therein, a disk mounted on
15 the seat and overlying the straight bore, a hollow and inverted frusto-conical shaped body fitted within the downwardly decreasing bore in the neck and having its upper end closed and its lower end resting on the
20 disk, the said body having diametrically op-

posed openings in the walls thereof registering with the recesses in the walls of the bore in the neck, a transverse tube located within the body and having its opposite ends secured to the body and its interior communicating with the openings in the walls of the body and with the recesses in the walls of the bore in the neck, and resilient means located within the tube and operable through the openings in the body and engaging in the recesses in the walls of the bore in the neck for securing the body within the bore. 25
30

In testimony whereof I, WILLIAM H. POLLGREEN, affix my signature in presence of 35
two witnesses.
